UNITED STATES PATENT OFFICE.

GOTTLIEB HÖRIG, OF LAWRENCE, MASSACHUSETTS.

MANGLE.

SPECIFICATION forming part of Letters Patent No. 738,448, dated September 8, 1903.

Application filed January 22, 1903. Serial No. 140,157. (No model.)

To all whom it may concern:

Be it known that I, GOTTLIEB HÖRIG, a citizen of the United States, residing at Lawrence, in the county of Essex and State of Massachusetts, have invented an Improvement in Mangles, of which the following description, in connection with the accompanying drawings, is a specification, like letters on the drawings representing like parts.

10 This invention has for its object the production of a novel apparatus, by which to iron sheets, pillow-cases, towels, handkerchiefs, &c.

15 My novel apparatus comprises a roller about which the article, preferably dampened, to be ironed is wound and a plurality of movable pressure-rollers coacting therewith, as will be described.

20 Figure 1 in front elevation represents an apparatus embodying my invention. Fig. 2 is a vertical cross-section of the same; and Fig. 3 is a detail section of the central roll B², to be referred to.

25 The framework consists, as shown, of end frames A and cross-girths A' A², each end frame, as shown, having a slot A³. The outer sides of the end frames have fixed to them bearing-plates B B', that sustain the ends of the shaft b of the central roll B². One end of the shaft b of roller B² has connected with 30 it a gear B³, with which meshes a pinion B⁴, mounted on a short shaft having its bearings in a part of the plate B', the shaft of the pinion having, as shown, an attached hand-wheel B⁵, by which to rotate the pinion and roller B². The front side of the framework sustains a suitable shelf B⁶. The roller B² has 35 connected with it one end of a sheet. (Partially shown in Fig. 3.) This sheet may be of any desired length, according to the length of 40 the article to be ironed, said sheet when the apparatus is not in use being drawn out or unwound from the roller B². The slots A³ above the roller B² receive boxes C, in which is entered the ends of the shaft of a roller C', 45 while the slots A³ below the roller B² receive boxes D, in which enter the ends of the shaft carrying the roller D'. The shaft of roller D', between the ends of the roller and the boxes D is embraced by the arms d of a yoke 50 D² having a central depending portion d², that is shown as connected to the inner end of a lever E, said lever being itself connected

by the strut E' and upright E³ to the treadle or lever E⁴, pivoted at E⁵ to the frame of the machine. The shaft of the roller C' is embraced by the arms G of a yoke G', in turn connected with the lever E between its ends by a spring connection G². The treadle or lever when depressed may be held in such position by a locking device H, shown as 60 having a shoulder h.

The person using the apparatus when the treadle is unlocked will pull the outer end of the sheet and unwind it from the roll B². Then the article to be ironed, the article or 65 the sheet being preferably dampened, will be laid out flat and smooth on the upper side of the sheet. Then the treadle will be depressed to move the lever E and force both rollers C' and D' against the roller B², and 70 the lever will be locked in its depressed position. The user of the apparatus will then rotate the wheel B³ and through the pinion B⁴ and wheel B⁵ will turn the roller B² and wind thereupon the sheet and the article to 75 be ironed that was laid on said sheet, the rotation of the roller B² being continued until the sheet and the article to be ironed are wrapped snugly about said roller B². During the rotation of the roller B², as described, 80 the rollers C' and D', forced toward the center of the roller B² by the lever E, will act on the sheet and through it on the article to be ironed, and as a result of the winding of the sheet and article under pressure the article 85 when removed by unwinding the sheet will be found to be ironed smoothly and needing no further ironing.

The inner end of the sheet is shown as attached to the roller B² by tacks but; instead 90 the said sheet may be attached to the roller in any other usual or suitable manner.

Having described my invention, what I claim, and desire to secure by Letters Patent, is—

1. An ironing apparatus comprising a central sheet-carrying roller, a plurality of pressure-rollers coacting with said central roller, two yokes, connected with the shafts of the pressure-rollers, a lever with which both said 100 yokes are connected, a second lever, and a strut and upright connecting said levers whereby force applied to the second lever will be transmitted through the first-men-

tioned lever to force said pressure-rollers toward the central roller.

2. An ironing apparatus comprising a central sheet-carrying roller, a plurality of pressure-rollers coacting with said central roller, two yokes connected with the shafts of the pressure-rollers, a lever with which both said yokes are connected, a second lever, a strut and upright connecting said levers to transmit force applied to the second lever through

the first-mentioned lever to the pressure-rollers, and a locking device for the second lever.

In testimony whereof I have signed my name to this specification in the presence of two subscribing witnesses.

GOTTLIEB HÖRIG.
